UNITED STATES PATENT OFFICE.

GEORGE A. SHIRER, OF PITTSBURGH, PENNSYLVANIA.

ARTIFICIAL HAND.

1,344,357.

Specification of Letters Patent. Patented June 22, 1920.

Application filed January 29, 1920. Serial No. 354,794.

To all whom it may concern:

Be it known that I, GEORGE A. SHIRER, a citizen of the United States, and resident of Pittsburgh, in the county of Allegheny and State of Pennsylvania, have invented a new and useful Improvement in Artificial Hands; and I do hereby declare the following to be a full, clear, and exact description thereof.

10 My invention relates to an attachment for cripples.

The object of my invention is to provide a device which may be readily clamped or attached to the forearm and provided with 15 means for securing in position thereon a knife, fork or tool of any convenient character, the method of securing the same in position being of such a simple character that no difficulty is encountered even by a 20 cripple in fastening or releasing same.

To these ends my invention comprises the novel features hereinafter set forth and claimed.

In the accompanying drawing, Figure 1 25 is a perspective view of my attachment showing the instrument in position thereon; Fig. 2 is a longitudinal section; Fig. 3 is a like view showing another position; and Fig. 4 shows a modified form of my invention.

30 In the drawing, the numeral 2 designates a cylindrical member divided longitudinally at 3 so as to overlap. The fastening means for securing the member 2 around the forearm or wrist 4 may be of any suitable character, that shown consisting of the hooks 5 adapted to be engaged by the hinged straps 6, said strap being provided with several 35 openings 7 to provide for adjustment for forearms of different sizes.

40 Riveted or otherwise secured to the member 2 at one end thereof is the keeper 8. A locking stud 9 is riveted or otherwise secured to the member 2 at or about the midportion thereof.

45 The shank 10 of a knife, fork, spoon or other instrument is formed of spring metal and is bowed as at 11 which forms the contact points 12 and 13. A slot 14 is formed in the shank 10, said slot being of sufficient 50 size to slip over the head 15 of the stud 9. The shank is inserted through the keeper 8 and advanced to the position indicated in dotted lines, Fig. 2, whereupon it is lowered into the position indicated in full 55 lines Fig. 2, whereupon the instrument is drawn back until the metal at the front

end of the slot 14 comes in contact with the neck 16 of the stud 9. In this manner the knife, fork, or other instrument is locked securely in position, the springiness 60 of the metal of the same acting by bearing at the points 12 and 13 to hold the instrument securely in position. This will be the position of the parts where there is a pressure rearwardly on the instrument, but where 65 there is an outward pull on the instrument as in lifting an object, the parts will take the position indicated in Fig. 3.

In Fig. 4, I have illustrated a modified form of my invention, in which a locking 70 dog 17 is pivotally mounted in the head of the stud 18, said locking dog having the lugs 19 and 20. In this construction, the shank is inserted as before through the keeper 21 and the slot 22 passes over the 75 stud 18 with the dog in raised position. When the shank has been seated where it is to be used in cases where the pressure is outward or downward, the dog will take the position indicated in Fig. 4 where the dog 80 engages the inner end of the slot 22. The lugs 19 form ends or projections for shifting the dog from one side to the other.

The device is of such simple character that the instrument may be inserted and 85 withdrawn by a cripple without assistance, and even where he is devoid of both hands.

What I claim is:

1. In an attachment for cripples the combination of a clamping member for the forearm, a keeper in said clamping member, a stud on said clamping member, and an instrument having a bowed shank portion engaging said keeper and having a slot 90 through which said stud projects to hold 95 said instrument in position.

2. In an attachment for cripples, the combination of a clamping member for the forearm, a keeper mounted thereon, a stud on 100 said clamping member, an instrument having a bowed shank portion adapted to pass through said keeper, said instrument having a slot through which said stud projects and a locking dog carried by said stud adapted to enter said slot.

In testimony whereof I, the said GEORGE A. SHIRER, have hereunto set my hand.

GEORGE A. SHIRER.

Witnesses:

ROBERT D. TOTTEN,
JOHN F. WILL.
